UNITED STATES PATENT OFFICE

ADOLPH G. LOTTER, OF MILWAUKEE, WISCONSIN, ASSIGNOR TO STATIONERS LOOSE LEAF CO., OF MILWAUKEE, WISCONSIN, A CORPORATION OF WISCONSIN

LOOSE-LEAF BINDER

Application filed August 31, 1928. Serial No. 303,211.

This invention relates particularly to loose leaf binders of the ring type and has as a general object to simplify and improve the construction of binders of this nature.

5 Another object of this invention resides in the provision of a loose leaf binder having separable sections which when engaged form a ring and having cam actuated means for moving the rings toward and away from each other.

10 A further object of this invention resides in the provision of a binder of the character described in which the ring sections are carried by plate members which are movable in substantially the same plane toward and away from each other, being actuated by cam means.

15 And a more specific object of this invention resides in the provision of a loose leaf binder of the character described in which the separable ring sections are carried by a pair of plate members mounted for movement in substantially the same plane toward and away from each other and having cam 20 slots with which studs carried by an actuating member engage to simultaneously move the plate members toward and away from each other upon movement of the actuating member.

25 With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

30 In the accompanying drawing I have illustrated one complete example of the physical embodiment of my invention constructed according to the best mode I have so far devised for the practical application of the principles thereof, and in which:

Figure 1 is a plan view of my improved loose leaf binder;

35 Figure 2 is a view similar to Figure 1 with the ring sections shown in their open position;

Figure 3 is a longitudinal, sectional view taken through Figure 2 on the plane of the line 3—3; and

Figure 4 is a cross-sectional view taken through Figure 2 on the plane of the line 4—4.

Referring now more particularly to the accompanying drawing, in which like numerals designate like parts throughout the several views, 5 represents a base plate to which 60 a cover member 6 formed of a single piece of flexible material is secured. An attaching plate 7 is suitably fixed to the medial portion of the cover member to form the back of the binder and from which a pair of tongues 8 extend to be passed through apertures 9 in the base plate 5 and then struck over to secure the plate 7, and consequently the cover member 6, to the base plate.

65 The plate 7 is further provided with a pair of upwardly extending projections 10 formed by pressing a portion of the metal outwardly to provide spacing members to maintain the plate 7 and the base plate 5 spaced from each other, for a purpose to be 70 later described, and the base plate 5 is struck downwardly, as at 19, to provide a depression or pocket with which the lip 8 engages to prevent its extending above the surface of the base plate.

75 Each end of the base plate 5 is struck over, as at 11, to provide guide-ways or retaining means spaced from the face of the base plate, the struck over portion 11 at one end having its medial portion 12 extended at substantially right angles to the base plate, to provide a convenient grip. Positioned above the base plate 5 and maintained in position by the struck over portions 11 is a pair 80 of movable ring carrying plates 13. The plates 13 have a plurality of ring sections 14 secured thereto by riveting and the plates are movable toward and away from each other to engage and disengage the ring sections.

85 Movement of the plates 13 is effected by a pair of cam slots 15 formed in each plate through which studs 16 pass, the studs being carried by an actuating member 17 positioned between the base plate and plate 7 carried by the cover member. The studs 16 also pass 90

through elongated openings 18 in the base plate and thus maintain the plates 13 and the actuating member 17 assembled with the base plate, the elongated apertures 18 being 5 parallel with the sides of the base plate to permit longitudinal movement of the actuating member and the cam slots being directed outwardly at an angle to impart transverse movement of the plates 13 upon longitudinal movement of the actuating member.

10 The longitudinal movement of the actuating member with respect to the base plate is limited by the length of the elongated slots 18 and is cut out, as at 20, to accommodate 15 one downwardly pressed portion 19 with which one lip 8 of the cover securing plate 7 engages and has one end fork-shaped to provide a recess 21 to accommodate the other depression 19. The opposite end of the actuating member is reduced in width and has its outermost end struck upwardly to provide a grip or finger engaging portion 22 to facilitate movement of the actuating member.

25 The cam slots 15 in the ring section of the mounting plates 13 are formed with portions 23 which extend for a short distance parallel to the longitudinal axis of the actuating member to provide locking means for retaining the ring sections against spreading.

30 Longitudinal movement of the actuating member in an outwardly direction to open the ring sections is prevented by the engagement of a locking lug 24 in a recess 25 in the adjacent end of the base plate, the locking lug 35 24 being mounted on an offset portion 26 of the actuating member which is yieldably positioned to extend the locking lug into the recess, disengagement being effected by a downward pressure of the grip 22, as will be 40 readily obvious.

As the riveted end portions of the ring sections extend beneath the lower surface of the plates 13, the adjacent portions of the base plate are provided with transverse channels 45 or grooves 27 which accommodate the riveted ends of the rings and provide transverse strengthening ribs for the base plate, the medial portion of the actuating member being offset as at 28 to accommodate the center channel 27. The sides of the base plate 50 29 are directed downwardly to substantially enclose the actuating member and provide a more finished appearance.

55 From the foregoing description, taken in connection with the accompanying drawing, it will be readily apparent to those skilled in the art to which an invention of the character described appertains, that I have provided novel means for opening and closing the ring sections of a loose leaf binder in which the opening and closing movement is positive and in which a simple locking means is provided to lock the ring sections in their 60 closed position.

I claim:

1. In a loose-leaf binder, a base plate, a plurality of separable ring sections, a pair of movable plates mounted above the base plate to which the ring sections are secured, whereby movement of the plates toward and away from each other opens and closes the ring sections, a longitudinally movably mounted actuating member, the base plate having elongated apertures parallel with the direction of movement of the actuating member and the movable plates having cam-shaped apertures, and pins carried by the actuating member and extending through the apertures in the base plate and the movable plates whereby movement of the actuating member simultaneously moves the plates toward and away from each other. 75

2. In a loose-leaf binder, a base plate, ring sections, plates to which the ring sections are secured and movable toward and away from each other to engage and disengage the ring sections, an actuating member longitudinally movably on the base plate, and means maintaining the base plate, the actuating member, and the movable plates assembled, said means being movable with the actuating member to cause simultaneous movement of the movable plates toward and away from each other upon actuation of the actuating member. 90

3. In a loose-leaf binder, a base, an actuating member movable longitudinally with respect to the base, a plate member movable transversely with respect to the base, a ring section carried by the plate member, the base having elongated apertures extending parallel with the direction of movement of the actuating member and the plate member having diagonal apertures, and securing means fixed to the actuating member and passed through the base and plate member apertures to maintain the several elements assembled and whereby longitudinal movement of the actuating member moves the plate member transversely with respect to the base. 100

4. In a loose-leaf binder, a base plate having an elongated aperture, a ring section, a member to which the ring section is secured and having a cam slot, means mounting the member for sidewise movement with respect to the base plate, an actuating member movable longitudinally with respect to the base plate, and means carried by the actuating member and passed through the base plate aperture and the cam slot whereby longitudinal movement of the actuating member moves the first mentioned member sidewise, and said cam slot having an extension into which the actuating member carried means is movable to restrain movement of said first mentioned member when the actuating member is in one position. 115

5. In a loose leaf binder, a base plate, a transversely movable member having a cam 120

slot, ring sections carried by said transversely movable member, an actuating member movable longitudinally with respect to the base plate, and means having a longitudinal sliding connection with the base plate and being movable with the actuating member and engaged in the cam slot of the transversely movable member for guiding the movement of the actuating member and imparting its movement to the transversely movable member.

In testimony whereof I have hereunto affixed my hand.

ADOLPH G. LOTTER.
